UNITED STATES PATENT OFFICE.

EDGAR JAMES, OF LINCOLNTON, NORTH CAROLINA.

PLOW.

996,718.

Specification of Letters Patent.

Patented July 4, 1911.

Application filed March 13, 1911. Serial No. 614,141.

To all whom it may concern:

Be it known that I, EDGAR JAMES, a citizen of the United States, residing at Lincolnton, in the county of Lincoln, State of North Carolina, have invented a new and useful Plow, of which the following is a specification.

This invention relates to that class of stirring or turning plows which are at the same time adapted for use as subsoilers, the several parts being operative either jointly or singly and successively, as will hereinafter more fully appear in connection with the complete description and the accompanying drawings, in which—

Figure 1 is a side elevation of the plow with the subsoiler projected; Fig. 2 is a similar view, partly in section, with the subsoiler in its normal elevated position; Fig. 3 is a plan view; Fig. 4 is a cross section on the line 4—4 of Fig. 2; Fig. 5 is a detail of one of the beams; Figs. 6 and 7 are details of the lever devices, and Figs. 8 and 9 are details of the subsoiler hereinafter described.

Throughout the following description and the accompanying drawings similar parts are referred to by like reference characters.

This improved plow comprises a pair of twin beams 10 and 11, the former or primary beam being stationary and secured rigidly in any approved manner to the turning plow indicated somewhat conventionally as having a landside 12 and a moldboard 13. The secondary beam 11 is pivotally connected at 14 to the front end of the primary beam, and at its rear end is movable downwardly between the landside and the moldboard. This secondary beam carries at its base or heel a subsoil share or bit 15, and the form and disposition of the twin beam are such that practically the whole of their combined strength is availed of in all adaptations of the implement.

As a simple and effective means to manipulate the secondary beam and subsoiler I have illustrated a hand lever 16, within convenient reach of the driver, permanently pivoted at 17 to an extension or shoulder 18 of the subsoil beam. This lever is connected to a fulcrum link or bar 19 whose lower end is permanently pivoted at 20 to any stationary portion of the turning plow. The connection between the lever and the link consists of a removable pivot pin or bolt 21 adapted to be inserted

in any pair of alining holes *a a'*, *b b'*, or *c c'*, according to the depth to which it may be desired to throw the subsoiler below its normal inoperative or elevated position. The normal elevation of the secondary beam 60 being a constant, its downward throw will always be substantially equal to twice the distance between the pivots 17 and 21, and the pivot 21 should be inserted in said holes considered in pairs so that the combined 65 effective length of the lever and link will be a constant, serving to maintain the secondary beam when elevated, snugly against a lug or abutment 22 on the primary beam. Furthermore, the pivot 21 swings with the lever 70 around the pivot 17 in an arc slightly greater than 180 degrees so that as the pivot just passes, at each end of its movement, the line joining the pivots 17 and 20, the lever and link constitute a substantial lock for the 75 subsoiler in any position of adjustment, such lock however being easily broken by hand operation of said lever when desired. Should occasion demand a more positive locking means for the hand lever, the same 80 may be added, and I have shown for such purpose a dog 23, operative by a hand grip 24, and adapted to engage the aforesaid extension 18 in either position of adjustment in a well known manner.

The rear edge of the secondary beam 11, below the extension 18, is adapted to engage a lug 25, shown as carried by the primary beam, so that when the subsoiler is in use the strain thereon will be borne by both 90 beams. Since the subsoiler is adjustable for different depths I prefer to make said rear edge of the secondary beam for a part of its length substantially concentric with the pivot 14, whereby the lug 25 will always 95 serve its purpose. When the beam 11 is elevated the front edge of its lower portion or heel engages a fixed stop or lug 26, carried on any convenient stationary member at the moldboard, as upon the beam 10, through 100 which the combined strength of the twin beams is utilized when the implement is used as a turning plow. Said beams together, therefore, need scarcely be heavier than the single beam as ordinarily used.

The subsoiler bit 15 is readily removable for sharpening and comprises a shank 15', secured in the socket 11' at the heel of the beam 11, and a shoe 15'' which extends rearwardly beneath and in contact with said 110

heel to protect the same and to prevent the bit from turning or twisting about the axis of the shank.

The implement may advantageously be used as a side-hill plow, for after a furrow is made in the usual way by the turning plow, by a simple manipulation of the lever 16 the subsoiler may be thrown down and applied to the same furrow in the reverse 10 direction, the means for changing from one form of the plow to the other being so easy of operation as to enable it to be accomplished while the team is making the turn at either end of the furrow and without a 15 moment's loss of time.

The several parts of the plow may be made of any materials that may be considered best adapted for their purposes, and I 20 wish too to be understood as not intending 20 to be limited to the specific details illustrated, reserving the right to vary therefrom without departing from the spirit of the protection hereby obtained.

I claim:

25 1. In a plow, the combination of a moldboard, a pair of twin beams, means to secure said beams to the moldboard whereby the effective strength of both beams is utilized during ordinary use of the moldboard, a 30 subsoiler bit secured to one of the beams, means to move the latter beam with relation

to the other to project the subsoiler bit below the moldboard, and means whereby the combined strength of both beams is made applicable to the subsoiler when projected, 35 substantially as set forth.

2. The combination of a moldboard, a primary beam secured thereto and having stop lugs at its top and rear portions, a secondary beam pivoted to the front end of the 40 primary beam, a subsoiler bit carried by the secondary beam, and hand operated means to throw and lock the secondary beam either up or down in engagement with the aforesaid lugs respectively, for the purposes set 45 forth.

3. In a plow, the combination of a moldboard, a stationary beam secured thereto, lugs, one at the top of said beam and another at the moldboard, a subsoiler beam 50 movably related to the aforesaid beam, and means to lock the beams together with the top of the latter beam against the one lug and with the front part of its lower end 55 against the other lug.

In testimony whereof I have hereunto affixed my signature in the presence of two subscribing witnesses.

EDGAR JAMES.
